WILLIAM WALLACE, OF EDINBURGH, SCOTLAND.

HYDRAULIC TELEMOtor.

1,307,281.

Specification of Letters Patent. Patented June 17, 1919.

Application filed February 25, 1919. Serial No. 279,139.

To all whom it may concern:

Be it known that I, WILLIAM WALLACE, a subject of the King of Great Britain and Ireland, and a resident of Edinburgh, Scotland, have invented certain new and useful Improvements in Hydraulic Telemotors, and of which the following is the specification.

In hydraulic telemotors for controlling ships' steering gear and the like, for operating indicators and for performing like functions at a distance, there is a transmitting apparatus and a receiving apparatus in which are pistons connected in a normally closed circuit so that the receiver piston (or 15 pistons) moves in normal synchronism with the transmitter piston (or pistons). But the receiver is apt in use to become out of correlation with the transmitter. Hitherto, in order to correct this fault there has been 20 provided in the transmitter a by-pass or equivalent device operating at mid-position of that apparatus to connect opposite sides of the hydraulic system momentarily, and in the receiver spring operated means for 25 moving that apparatus to mid-position when the transmitter by-pass is momentarily in operation—thus bringing transmitter and receiver again into proper correlation each time mid-position is reached. However, it 30 is apparent that by the time the transmitter has reached the end of its stroke there may be a certain want of correlation—uncorrected until mid-position is passed again and obviously becoming greater and greater if the 35 apparatus be operated for a time without its reaching the only point at which correlation can again be established—namely, mid-position.

The invention has for its object to overcome this disability, and by providing means for establishing correlation between transmitter and receiver at a series of points in their strokes to produce a telemotor of an accuracy of movement very much greater 45 than that of those hitherto generally in use.

According to the invention there is provided in the transmitter a by-pass device—that is to say, a device momentarily connecting the opposite sides of the hydraulic system—which is mechanically operated from the mechanism operating the transmitter piston or pistons to make connection between opposite sides of the system momentarily at 50 a series of determinate positions in the stroke 55 of the transmitter. There is operatively

connected to the receiver a device operated mechanically from its piston or pistons and adapted to move that apparatus to a corresponding position synchronously with the operation of the transmitter by-pass at 60 each and all of the series of determinate positions. Thus, whenever the transmitter reaches a determinate by-passing position, the receiver is automatically brought exactly to the corresponding position to which 65 it is of course adjacent in any case.

The by-pass device operated from the transmitter may comprise valves or cocks of any convenient type. It is operated by intermittent gearing or cam mechanism from 70 the gearing by which the piston or pistons of the transmitter are moved in suchwise that by it communication is momentarily established between opposite sides of the hydraulic system at a series of determinate 75 points in the stroke of the transmitter. This by-pass device preferably controls also the usual supply of replenishing or make up liquid.

The receiver-correcting device consists of 80 spring or equivalently loaded means for intermittently imposing on the receiver piston or pistons a force tending to bring it (or them) to a series of positions corresponding with the open by-pass positions of the transmitter—that is to say, so applying a force to the receiver piston that it is brought into correlation with the corresponding transmitter position whichever direction therefrom it may have strayed. This device may 85 very conveniently consist of crank or cam mechanism operatively connected through gearing with the receiver piston and so spring-loaded that it tends to assume a definite position—the gearing being so proportioned that it tends to assume a series of successive similar positions correspondingly with the successive positions of the transmitter operated by-passing devices. 95

When the improved telemotor is used for 100 indicating a series of definite positions on dials—for example, as when applied to a ship's telegraph or the like—the pointers traversing the dials at the transmitting and receiving stations may be operated from the 105 respective instruments by step-by-step mechanism such as the well-known "Geneva" movement.

It will be seen that in the improved telemotor there is provided an apparatus in 110

which definite correlation of the receiving device with the transmitting device is attained and maintained indefinitely.

- An illustrative example of the application 5 of the invention to a ship's telegraph is shown in four accompanying sheets of explanatory drawings, Figures 1 and 2, Sheet 1, being respectively sectional front and sectional side elevations of the transmitter, 10 Figs. 3 and 4, Sheet 2, like views of the receiver, while Figs. 5, 6, 7 and 8, Sheet 3, are views of the transmitter detailed, and Fig. 9, Sheet 4, a diagrammatic general arrangement of the whole plant.
- 15 The transmitter is of that type having two vertical cylinders A side by side in which operate rams A¹ having on them racks A² engaged by a pinion A³ intermediate to them, so that on its rotation the 20 rack-bearing rams are moved in opposite directions. The pinion A³ is fast on a transverse shaft B in the housing, on which shaft is fast a spur-wheel B¹ engaged by a pinion C fast on a shaft C¹ having on its outer end 25 a handwheel C² by which the transmitter is operated.

On this handwheel shaft C¹ is fast the single-toothed gear D of a "Geneva" step-by-step movement (Fig. 5) the corresponding wheel D¹ of which is on a short shaft D² connected by a pair of bevel wheels D³ with a shaft bearing a pointer D⁴ traversing a dial D⁵ having the usual indications.

The handwheel shaft C¹ has also on it a 35 disk E (Figs. 6 and 7) which has fixed on it an arc E¹ of bevel teeth which gear intermittently with a bevel pinion E² on a vertical shaft E³. The disk E is also so formed as to act as a lock between the shafts C¹, 40 E³, when the arc E¹ is not in engagement with the pinion E², and to this end is of such diameter that it bears against one or other of the faces of a hexagon disk E⁴ fast on the spindle E³ at all points of its circumference except near the arc E¹, at which point there is cut in it a gap E⁵ to permit of rotation of the shaft E³.

On the lower end of the shaft E³ is formed a packed parallel-plug cock F (Fig. 50 8). In this cock are three ports which may be caused as shown in Fig. 8 to interconnect the two cylinders A by way of passages F¹, F² with each other and jointly by way of a passage F³ with the usual supply of 55 make-up liquid. In intermediate positions the cock of course closes these connections.

The gearing between the parts is such that once for each revolution of the handwheel C² the cock is operated to by-pass the cylinders A—⁶⁰ that is, to throw them into communication with each other and with the make-up supply. At the same time, the pointer D⁴ is caused by the Geneva movement to traverse one division of its dial D⁵. Thus, step-by-step—one for each revolution

of the handwheel C²—the pressure upon opposite sides of the system is equalized by the opposite sides being thrown into communication.

As regards the cylinders, rams and their 70 allied parts (which are therefore given the same reference characters) the receiver shown in Figs. 3 and 4 is substantially identical with the transmitter—that is to say, rack-bearing rams A¹ operate in cylinders A and engage a pinion A³ on a shaft B. The shaft B in this case extends laterally out through the casing and bears on its end a pointer G traversing a dial G¹ bearing indications corresponding with those on the transmitter 75 dial D⁵. On the shaft B is also a spurwheel H gearing with a pinion H¹ on a parallel shaft H² beneath it. On the end of this shaft is a crank H³ the pin of which is engaged by a connecting rod H⁴ sliding upon a 80 rod H⁵ anchored to a pin H⁶ fast on the casing. Between cups H⁷ (one of which is adjustable) on these rods H⁴, H⁵ is arranged a helical spring H⁸ in compression and thus 85 always tending to throw the crank H³ to 90 the top of its stroke—in which position it is shown.

On the shaft H² is the single toothed pinion J of a Geneva movement, the wheel J¹ of which is loose on the shaft B and carries 95 pointer G. These are similar to what is shown in Fig. 5 as applied to the transmitter and serve to steady the movements of the pointer G.

The gearing is so proportioned in transmitter and receiver that as the former reaches each by-passing station the crank H³ is at the top of its stroke if no leakage has taken place. If any leakage has taken place, however, and the crank is therefore not precisely at that point, it is apparent that the operating liquid being at this moment free to pass from one side of the system to the other, the spring H⁸ will forthwith throw the crank to the top of its stroke and so bring the receiver into agreement with the transmitter. Further movement of the transmitter handwheel C² of course immediately closes the by-pass connection, and the receiver again commences to move in synchronism with the transmitter until the next by-passing station is reached, by which time the crank is again at the top of its stroke, and correction (if it be not quite there) again takes place.

In the diagram of an installation shown in Fig. 9, transmitter and receiver are connected by the usual line pipes K, L, while the by-pass valve box M is connected by a pipe M¹ with the usual make-up tank M².

It is essential that the system should as far as possible be freed from air occluded in the operating liquid and otherwise present, and to that end there are provided on the transmitter and receiver cylinders air 130

release valves N (these of ordinary needle type are to be seen in detail in Fig. 8). Pipes P connect the cylinders of the receiver by way of stop valves P¹ respectively with 5 a pump P² and with a reservoir P³ of the liquid used. A pipe P⁴ in turn connects the reservoir with the pump P² which is of ordinary plunger form operated by a hand-lever P⁵.

10 In order to free the system from air, the air release valves N and the stop valves P¹ are opened and the transmitter is placed in by-passing position. The pump is then operated and liquid is circulated through the 15 system until it issues from the valves N which are then closed. Pumping is continued until the discharge to the tank P³ pulsates synchronously with the strokes of the pump. The stop valves P¹ are then 20 closed and the system is ready for work.

Mechanical or electrical devices for giving audible signals may be operatively connected to one or both instruments.

It is to be understood that the foregoing 25 example is illustrative only, and that the details of the carrying out of the invention may be somewhat widely varied without departing from its essence, which is the provision of means in the transmitter for by-passing the system at successive points in 30 combination with means for bringing the then-relieved receiver into correlation.

What I claim is:—

1. In a telemotor system having piston-and-cylinder transmitting and receiving instruments; means in the transmitting instrument for by-passing the system at successive points and means for bringing the receiving instrument when it is then relieved 40 into correlation.

2. A telemotor system forming the subject-matter of claim 1 hereof, comprising a by-pass valve device mechanically operated from the handwheel of the transmitting instrument and momentarily inter-connecting 45 opposite sides of that system with one another and with a make-up supply during the rotation of the handwheel.

3. The telemotor system forming the subject-matter of the foregoing claims hereof, comprising a multi-ported plug cock controlling connection between opposite sides of

the system and operated by intermittent gearing from the handwheel of the transmitting instrument.

55

4. A transmitting instrument for the telemotor system forming the subject-matter of the foregoing claims hereof comprising two rack-bearing rams operating in cylinders and engaged by a pinion between them 60 which pinion is operatively connected to a handwheel, a train of interrupted gearing operating a plug cock controlling communication between opposite sides of the system and operated from said handwheel, means 65 for locking said cock against rotation during its interrupted periods and means for operating from the handwheel a pointer traversing a dial.

5. The telemotor system forming the subject-matter of claims 1 to 3 hereof, comprising receiver-correcting means consisting of a spring or equivalently controlled device adapted to successively return the receiver parts to correlation when the system is freed 75 by the successive operations of the by-passing device.

6. The telemotor system forming the subject-matter of claims 1 to 3 and 5 hereof, comprising receiver correcting means consisting of a crank so operatively connected to the receiver piston or pistons that it is normally moved to a position at which it is held by a spring or equivalent successively at each successive by-passing motion in the 85 transmitting instrument.

7. A receiving instrument for the telemotor system forming the subject-matter of the foregoing claims hereof, comprising rack-bearing rams operating in cylinders 90 and engaging a pinion between them which pinion is connected by gearing to a crank, a spring operatively connected to the crank in suchwise as to cause it to seek a determinate position, the crank being so placed 95 and the gearing which operates it being constructed and arranged to cause the crank to be normally at that position when successive by-passings take place in the transmitting instrument.

100

In testimony whereof I have signed my name to this specification.

WILLIAM WALLACE.
